UNITED STATES PATENT OFFICE.

ADELBERT J. GRINNELL, OF WALTHAM, MASSACHUSETTS.

ANTIFRICTION-BEARING.

SPECIFICATION forming part of Letters Patent No. 598,317, dated February 1, 1898.

Application filed February 1, 1897. Serial No. 621,385. (No model.)

To all whom it may concern:

Be it known that I, ADELBERT J. GRINNELL, of Waltham, in the county of Middlesex and State of Massachusetts, have invented certain 5 new and useful Improvements in Antifriction-Bearings, of which the following is a specification.

This invention has relation to antifriction-bearings for shafts, and more especially for 10 the crank-shafts of bicycles; and it has for its object to provide such improvements in the same as will render them more durable and decrease the element of friction to a minimum.

15 To these ends the invention consists in the improvements in devices of the character specified, such as are illustrated in the accompanying drawings and now to be described in detail and then pointed out in the appended claims.

20 Reference is to be had to the drawings and to the letters marked thereon, forming a part of this specification, the same letters designating the same parts or features, as the case 25 may be, wherever they occur.

Of the drawings, Figure 1 represents in side elevation, with a portion broken away, a crank-hanger equipped with my improvements. Fig. 2 is a central vertical section on 30 the line 2 2 of Fig. 1 and looking in the direction of the arrow. Fig. 3 shows in perspective the spider and one of the rings, one of the disks being in position to be inserted in the spider. Figs. 4 and 5 illustrate another 35 embodiment of the invention. Figs. 6 and 7 illustrate another form of spider.

In the drawings, *a* represents a barrel or hanger which is formed or secured to the converging bars *b* *b'* *b*² of the bicycle-frame.

40 *c* indicates the crank-shaft, which is formed with a rigid hardened cone *c'* and an adjustable hardened cone *c*² in threaded engagement therewith.

The barrel or hanger is formed with internal flanges *a'* *a'*, against which hardened bearing-rings *d* *d* abut, being threaded into the internally-threaded ends of the barrel. As each end of the hanger is provided with the same device and constructed in the same 45 way, I shall describe only one, and it will be understood that the description will be equally applicable to the other.

e indicates a spider which is U-shaped in

cross-section, as shown in Fig. 2, and in which are journaled disks *f*, which are preferably 55 three in number. Each disk is mounted upon a pin *f*, passed through the flanges *e'* *e*² of the spider and projects through an aperture *e*³ in the spider, so as to have its periphery bear against the bearing-cone *c'* *c*². Each disk is 60 also formed with oppositely-extending hubs *f*² *f*³, the first of which bears against the inner edge of the ring *b* and the other of which bears against the flange *g'* on the outer ring *g*, which is externally threaded and is screwed 65 into the end of the hanger or barrel.

70 Preferably the ring *g* is formed with an outwardly-projecting flange *g*², which abuts against the end of the barrel, so as to tightly close the same, and the ring *d* is also provided with apertures *d*³ to receive a spanner or other suitable tool by means of which the ring may be removed or secured in place. Now it will be seen that each disk bears against the cone at its periphery, its two hubs bearing against 75 the inner edges of the two rings *d* and *g*, both of which are hardened, the disks being likewise hardened, so as to increase their wearing qualities. The flange *e'* of the spider is wider than that at *e*² and extends up outside the 80 flange on the ring *g*, so as to loosely secure the spider and the said ring *g*.

75 In securing the parts in place the ring *d* is first screwed in until it abuts against the flange *a'*. Then the spider *e* is inserted 85 through the aperture in the ring *g* until the flange *g'* of the latter bears against the flange *e'* of the spider. Then two of the disks are inserted in place by slipping them between the flange *e'* and the flange *e*² of the spider, and 90 the other disk is inserted in place, as shown in Fig. 3, there being a recess in the flange *e*² to permit its insertion.

When the parts consisting of the ring, the spider, and the disks are all assembled, they 95 are placed in the end of the barrel, and the ring *g* is screwed tightly in place. Then the shaft *c* is inserted and the cone *c*² is adjusted until both sets of disks bear evenly at their peripheries on the cone and at their hubs on 100 the rings.

For the purpose of preventing the accumulation of dust and dirt in the barrel I provide dust-guards consisting of rings *h*, which may be forced into rabbets in the rings *g*. 105

Instead of forming the spiders U-shaped in

cross-section, as shown, I may form them of two parallel rings $m\ m'$, connected together by shouldered rivets m' , as shown in Figs. 8 and 9.

5 In Figs. 4 and 5 I have illustrated another embodiment of my invention in which I dispense with the spider. Referring to these last-mentioned figures it will be seen that I employ two hardened rings j and k , which are secured together by rivets k' , having spacers k^2 , both rings being recessed, as shown in Fig. 4, to receive the hubs of the disks l . In this construction the rings are not threaded into the end of the barrel, but are forced in and held against rotation by a key k^3 . Thus from the foregoing it will be observed that I have provided a construction which is extremely simple and which at the same time is highly efficient in operation and possesses great durability and wearing qualities.

20 Each disk bears at three points, (one point with its periphery against the cone and at two points with its hub against the rings,) and by reason of its relatively large diameter (as compared with the ordinary antifriction roll or ball) reduces the friction and requires less power to rotate it.

25 In the construction shown in Figs. 1 to 3 the spider and the rolls may travel relatively to the rings and the latter are held at a predetermined distance apart, and in the construction illustrated in Figs. 4 and 5 the disks are inserted loosely in place and bear loosely against the rings and are capable of traveling around the same and the cone, being properly spaced by their engagement with each other. In both of these constructions, which I have described hereinbefore, the disks are all free not only to revolve around the axis 30 of the shaft, but are also adapted to revolve about the rings, each disk bearing with its periphery against the shaft (or the cone on the shaft) and having an oppositely-extending hub bearing against the edges of the ring.

40 45 By this peculiar arrangement the friction is reduced to a minimum.

45 I have stated that the rings are revoluble about the shaft, for of course it will be understood that the cones are to all intents and purposes a portion of the shaft, but may be omitted, if desired.

I claim—

1. A bearing for a shaft comprising a hanger or barrel, two parallel rings inserted in each end, and a series of disks revoluble about the axis of the shaft and adapted to roll around said rings, said disks each bearing with its periphery against the shaft and having an oppositely-extending hub bearing against the inner edges of the rings. 55

2. In combination, a shaft having cones, a barrel or hanger, two parallel rings inserted in each end of the barrel, and a series of disks all revoluble about the shaft and adapted to roll around the rings, said disks having their peripheries bearing against the cones, and having oppositely-extending hubs bearing against the said rings. 60

3. In combination, a shaft having cones, a barrel or hanger, two parallel rings inserted in each end of the barrel, a series of disks all revoluble about the shaft and adapted to roll around the rings, said disks having their peripheries bearing against the cones and having oppositely-extending hubs bearing against 75 the said rings, and means for spacing said disks. 70

4. A bearing for a shaft having cones comprising a barrel or hanger, two parallel rings inserted in each end of the barrel and having a space between them, a series of disks freely revoluble about the axis of the shaft and each provided with an oppositely-projecting hub, said disks each bearing with its periphery against the cone, and with its hub against 85 the inner edges of the rings, and spiders in which said disks are mounted. 80

5. The combination with a shaft, and a barrel, of parallel separated rings arranged in said barrel, a spider arranged between the rings and the shaft and having flanges, and a series of disks journaled in the flanges of the spider, and bearing with their peripheries against the shaft, and having hubs bearing against the inner edges of the rings. 90

95 In testimony whereof I have signed my name to this specification, in the presence of two subscribing witnesses, this 29th day of January, A. D. 1897.

ADELBERT J. GRINNELL.
